UNITED STATES PATENT OFFICE.

VICTOR R. DESPARD, OF VALPARAISO, INDIANA, ASSIGNOR TO MCGILL MANUFACTURING COMPANY, OF VALPARAISO, INDIANA, A CORPORATION OF INDIANA.

SWITCH MOUNTING.

Application filed April 27, 1922. Serial No. 556,897.

To all whom it may concern:

Be it known that I, VICTOR R. DESPARD, a citizen of the United States, residing at Valparaiso, in the county of Porter and State of Indiana, have invented a certain new and useful Improvement in Switch Mountings, of which the following is a full, clear, concise, and exact description, reference being had to the accompanying drawings, forming a part of this specification.

My invention relates to switch mountings and is more particularly concerned with the production of a casing combined with a switch mechanism whereby such structure may be with safety mounted inside of canopies or other enclosed or semi-enclosed places. Switch structures are very largely mounted within canopies and special provision must be made in order to prevent the establishment of a fire hazard. The Board of Fire Underwriters requires that there shall be no exposed terminals or if exposed that they shall be amply protected by a metal covering or casing.

My invention concerns itself with the provision of a structure of this character and I will explain one form which it may take by referring to the accompanying drawing, in which—

Fig. 1 is a fragmentary side view partly in section of a canopy equipped with my improved device;

Fig. 2 is a side view of my improved device;

Fig. 3 is a sectional view on line 3—3 of Fig. 1, the actual switch mechanism not being shown;

Fig. 4 is a perspective view of one of the casing elements;

Fig. 5 is a perspective view of the other casing element;

Fig. 6 is a side view of the interior mechanism adapted to be enclosed by the casing shown in Figs. 4 and 5; and

Fig. 7 is a nut for securing the hub in position.

Referring to the drawing, I show a canopy 10 which is desirably mounted against the ceiling and which may support any suitable electric fixture or bowl such, for instance, as by the chain 11. A control switch 12 of my improved design is mounted within the canopy and is suitably operated or controlled through the agency of the lever 13 and chain

My improved switch structure contemplates two base plates 15 and 16 which are held together through the agency of two brackets 17 and 18 which brackets also carry the connecting screws 19 and 20. Suitable switch contacts 21 are provided which cooperate with a movable switch element 22 which switch element is moved from one alternative position to the other by means of the lever 13. The switch structure includes a supporting plate 24 secured to which is a screwthreaded hub 25 adapted to project through the wall of the canopy 10. The knurled thumb nut is then mounted in place upon the screwthreaded element 25 to thereby hold the structure tightly in position within the canopy. Conductors 27 and 28 lead outwardly from the switch structure, being connected respectively into circuit by the binding screws or terminals 19 and 20, these screws forming the connection terminals for the device.

My invention in addition to what has been already stated concerns itself particularly with the provision of a suitable casing for the switch structure as carried by the base plates 15 and 16, which casing must be of such a nature that the connection terminals 19 and 20 are properly concealed, thus to prevent the establishment of a fire hazard. The casing consists of the two elements 29 and 30, the member 30 forming a cap in this particular instance. The cap 30 has punched out lugs 31 and 32 projecting inwardly which are adapted to register with corresponding openings such as the opening 33 provided in the shell part 29. When the two parts 29 and 30 are thus placed in juxtaposition, the notches 31 and 32 snap into their proper relationship and the shell is tightly closed. Relative rotation of the parts 29 and 30 is prevented due to the oblong outline of these parts. The shell part 29 has a slot 34 which accommodates for the projecting supporting plate 24 projecting therethrough. The casing 29 also has two cutaway portions 35 which form the outlet for the conductors 27 and 28. The cap 30 also has cutaway portions both in its sides and in its top face as shown at 36 to form outlets for the said conductors 27 and 28. It will be seen that as a portion of the side walls of the shell 29 is cutaway and also registering portions of the top wall of the cap 30, that an opening is provided which ex-

2

tends diagonally relative to the vertical axis of the device as represented, for instance, by the line 3—3 of Fig. 1. The object of this is that the conductors 27 and 28 may thereupon either leave the structure in a vertical manner as shown in Fig. 1 or in a horizontal manner as shown in Figs. 2 and 3. This is of importance in view of the fact that devices of this kind are placed in small and 10 very restricted space so that at times it is necessary to have these conductors extend outwardly either in one direction or another. In order to properly conceal the connection terminals 19 and 20, I line the shell portion 29 with a complete lining of insulation 37 which lining is cutaway to register with the slot 34 but is not cutaway to as large an extent as the slot 35 so that this insulating lining 37 as shown more 20 clearly in Figs. 1 and 4 overhangs the opening 35 and thus prevents contact between the conductor 28 and the shell portion 29. The cap 30 is similarly provided with a lining 38 which overhangs the edge of the opening 39 in said cap. This likewise prevents the conductor from touching any portion of the metal of the cap. By reason of this construction a complete frame of insulation overhangs the outlets of the casing, 30 which insulating frame is also of sufficient extent, as shown more clearly in Fig. 3, to entirely cover the connection terminals 19 and 20. The device thus conforms to the present requirements of the Board of Fire 35 Underwriters and eliminates the fire hazard.

It will be noted that the insulation portion of the incoming circuit conductors 27 and 28 covers the otherwise exposed metallic portions 17 and 18 so that the electrical parts of the entire device are completely 40 protected by insulating material.

From what has been thus described it is thought that my invention will be readily clear to those skilled in the art. It will be 45 clear that the specific form selected for illustration herein is merely to be construed as being one of the many forms which my invention may take.

What I claim as new and desire to secure 50 by Letters Patent is:

1. In a device of the character described, a housing comprising a hollow body portion and a cap member, said body portion having a cut out portion in the edge thereof and said cap member having an interrupted flange embracing said body portion, an interruption in said flange lying opposite said cut out portion, the end wall portion of said cap having a cut out portion adjacent said interruption in said flange.

2. In a device of the character described, a housing comprising a hollow cup-like body portion and a flanged cap member, the edge of said body portion having a plurality of notches therein and the flange of said cap

member being interrupted at a plurality of points, the interruptions in said flange lying opposite said notches when said body portion and cap are assembled, said cap member having notches in the end wall thereof adjacent the interruptions in said flange, whereby the notches in said body portion and cap form corner openings in said housing.

3. In a device of the character described, a housing comprising a body portion having a side wall portion provided with notches in the edge thereof and a cap having a flange embracing said side wall, said flange being interrupted opposite said notches and an end wall having notches aligning with the notches in said body portion.

4. In a device of the character described, a metallic housing comprising a hollow cup-like body portion and a cap member having a flange embracing said body portion, said body portion having a notch in the edge thereof, said flange being interrupted opposite said notch and an insulating lining for said housing comprising a cup-like insulating member fitting within said body portion and having a notch in the edge thereof opposite and smaller than the notch in said body portion to provide a projecting lip of insulating material at said notch.

5. In a device of the character described, a metallic housing comprising a hollow cup-like body portion and a cap member having a flange embracing said body portion, said body portion having a notch in the edge thereof, said flange being interrupted opposite said notch and the end wall of said cap having a notch therein aligning with the notch in said body portion and an insulating lining for said housing comprising a cup-like insulating member fitting within said body portion and having a notch in the edge thereof opposite and smaller than the notch in said body portion to provide a projecting lip of insulating material at said notch, and a flat insulating member lining said cap and having a notch in the edge thereof opposite and smaller than the notch in said cap to provide a projecting lip of insulating material at the notch in said cap.

6. In a device of the character described, switch mechanism, a mounting therefor comprising wiring terminals, a metallic housing comprising a hollow cup-like body portion and a cap member having an interrupted flange embracing said body portion, said body portion having notches in the edge thereof opposite said wiring terminals and an insulating lining for said housing comprising a hollow cup-like member of insulating material having notches in the edge thereof opposite and smaller than the notches in said housing, to provide a projecting lip of insulating material at each of

said notches, said lips of insulating material protecting said wiring terminals.

7. In a device of the character described, switch mechanism, a mounting therefor comprising wiring terminals, a metallic housing comprising a hollow cup-like body portion and a cap member having an interrupted flange embracing said body portion, said body portion having notches in the edge thereof opposite said wiring terminals and said cap having notches in the end wall thereof aligning therewith and an insulating lining for said housing comprising a hollow cup-like member of insulating material having notches in the edge thereof opposite and smaller than the notches in said housing, to provide a projecting lip of insulating material at each of said notches, said lips of insulating material protecting said wiring terminals and an insulating lining for said cap having notches opposite and smaller than the notches in said cap to provide a projecting lip of insulating material at each of the notches in said cap, whereby an insulating barrier surrounds each of the resulting corner openings in said housing.
8. In a device of the character described, switch mechanism, a metallic housing therefor having a side and an end wall portion, said housing being provided with an opening extending into said side and end wall portion and an insulating lining for said

housing having an opening therein opposite the opening in said housing, the edge of said lining extending beyond the edge of said housing at said opening to provide a projecting barrier of insulating material between a conductor lying in said opening and said metallic housing.

9. In a device of the character described, switch mechanism, a mounting therefor, a metallic housing therefor comprising a body portion and a cap member, said body portion having a conductor receiving notch in the edge thereof and insulating means mounted in said cap and said body portion collectively forming a projecting barrier between said metallic housing and a conductor placed in said notch.

10. In a device of the character described, switch mechanism, a mounting therefor, a metallic housing therefor comprising a body portion and a cap member, said body portion having a conductor receiving notch in the edge thereof and a pair of insulating members mounted in said cap and said body portion collectively forming a projecting barrier between said metallic housing and a conductor placed in said notch, said members lying on opposite sides of said conductor.

In witness whereof I hereunto subscribe my name this 15th day of April, A. D. 1922.

VICTOR R. DESPARD.
